United States Patent Office

Des. 232,502

Patented Aug. 27, 1974

232,502

UTILITY STAND

Joseph P. Richterich, Carouge, Switzerland, assignor to
Prodonta S.A. Geneva, Switzerland

Filed Sept. 25, 1972, Ser. No. 291,577

Claims priority, application Switzerland May 24, 1972

Term of patent 14 years

Int. Cl. D6—06; D24—99

U.S. Cl. D6—130

FIG. 1

FIG. 3

FIG. 2

FIG. 4

FIG. 1 is a front elevational view of a utility stand incorporating my new design.

FIG. 2 is a top plan view thereof.

FIG. 3 is an end elevational view thereof.

FIG. 4 is a rear elevational view thereof.

The end opposite that shown in FIG. 3 is identical to the end shown and the bottom is plain, having no ornamental features.

I claim:

The ornamental design of a utility stand, substantially as shown and described.
